Application April 25, 1950, Serial No. 157,970

5 Claims. (Cl. 312—311)

1

This invention relates to an article of furniture, and more particularly to a convertible and adjustable article of furniture, and features thereof.

The article referred to is a convertible desk and cabinet combination which includes a desk panel which can be placed in an inoperable, out of the way position permitting use of the article as a cabinet. When the desk panel is in its operable position, the article provides an ingenious means for adjusting the height and orientation of the desk panel.

One object of the invention is to provide an article of furniture including a desk panel which may be placed in an inoperable, out of the way position within the article, permitting the article to be used as a cabinet, and which may also be disposed in an operable position for use of the article as a desk.

Another object of the invention is to provide an article of furniture as set forth in the preceding object, wherein there is included novel structure providing adjustment of the desk panel when in operable position.

A further object of the invention is the provision of an ingenious arrangement for adjustably positioning a desk panel.

Yet another object of the invention resides in the provision of an article of furniture and the features referred to above, wherein simplicity of construction and ease of operation is an important advantage.

These and other objects of the invention will be apparent from a study of the following specification when read in connection with the accompanying drawings, wherein:

Fig. 1 is a perspective view of the article with the desk panel in inoperable position within the cabinet and with the doors of the cabinet closed;

Fig. 2 is a view similar to Fig. 1 but with the doors open and the desk panel in an operative position;

Fig. 3 is a sectional view looking downwardly on Fig. 2, and taken below the level of guide 21 but above panel 25;

Fig. 4 is a left hand side elevational view of the article as shown in Fig. 2, but with the right side panel and right door removed;

Fig. 5 is a plan view of the left hand end of the article with the left door shown in open position and the desk panel in its inoperative position, the top panel of the desk being removed to show the inside structure;

Fig. 6 is a detail plan view, partly in section looking down on the left rear corner of the desk

2

panel and associated structure in the position shown in Fig. 2;

Fig. 7 is a side elevational view, partly in section of the structure shown in Fig. 6; and

Fig. 8 is a perspective view of the upper left hand front corner of the cabinet with the top panel, doors and desk panel removed.

Referring now to the drawings in more detail, there is shown a cabinet having a bottom 10, a back 11, end panels 12 and 13, and a top panel 14. The front of the cabinet is closed (Fig. 1) by doors 15 and 16 hinged to the front edges of end panels 12 and 13. Doors 15 and 16 each have on their inner surfaces a plurality of spaced holes 17 located at varying elevations above the bottom edge of each door. For each hole 17 in door 15, there is a corresponding hole in door 16 located at the same elevation. The holes 17 receive pegs 18 (Figs. 3 and 4) and these pegs may be placed in any of the holes 17, it being understood that the two pegs 18 will ordinarily be positioned in corresponding holes in the two doors for a purpose which will be explained presently.

As best seen in Figs. 4, 6, 7 and 8, each end panel 12, 13 is provided along the upper part of its forward edge portion with a guideway formed by a pair of spaced guides, the forwardmost one of which (20) extends upwardly to the level of the upper edges of the end panels, while the rearward guide (19) terminates at its upper end a substantial distance below the upper edge level of the end panels 12, 13. The extreme front portion of each guide 21 is of enlarged width as shown at 22. This enlargement may be integral or may consist of a block attached to guide 21 as is shown in Fig. 8.

As shown particularly in Figs. 4, 7 and 8, a plurality of spaced holes 23 are located in the end walls 12, 13 in the guideways formed by guides 19, 20. For each hole 23 in one end panel there is a corresponding hole at the same level in the guideway in the other end panel, and there is a peg 24 located in each series of holes 23, the two pegs being customarily placed in corresponding holes of the two series of holes 23.

A desk panel is shown at 25, this panel having a depth from front to rear smaller than the similar internal dimension of the cabinet with the doors closed. From end to end, the desk panel is slightly smaller in dimensions than the distance between the guides 19, 20 on end panel 13 and the corresponding guides on end panel 12. At each rear corner, panel 25 has a projection 26 extending beyond each end edge of

the panel so that at its rear edge, the panel has a length only slightly smaller than the distance between the inner surfaces of the two end walls in the region of the two guideways formed by guides 19 and 20. From front to rear, the projections 26 are slightly smaller than the width of the guideways formed by guides 19, 20.

From the description of the parts which has now been given, the manner in which the various parts cooperate should be readily understood.

It will be seen from the drawings that desk panel 25 may be disposed in an inoperative position as shown in Fig. 5, in which the desk panel is positioned closely adjacent the under surface of top panel 14 so as to leave practically the entire interior space of the cabinet available for storage or other use. In this position, the desk panel is supported by projections 26 resting on the rear ends of guides 21, and by the front corners of panel 25 resting on enlargements 22. It will be seen that the positioning of guides 21 and the thickness of panel 25 govern the degree of proximity of panel 25 and top panel 14.

It will also be seen that with doors 15, 16 open, desk panel 25 may be placed in a plurality of operative positions in which the projections 26 are located in the guideways formed by guides 19 and 20, the height of these projections and the rear edge of panel 25 being governed by the positions of pegs 24 upon which these projections rest. The holes 23 and pegs 24 thus provide, in effect, a variable height hinge and support for the rear edge of panel 25, permitting swinging of the front edge of the panel to a plurality of elevations relative to the rear edge of panel 25.

Downward movement of the front edge of panel 25 may be limited by placing pegs 18 in the holes 17 which are located at the desired height. By adjusting the position of pegs 18 the height of the front edge of panel 25 may be adjusted as desired.

It should now be clear that by appropriate positioning of pegs 24 and 18, the orientation of panel 25 may be varied within a wide range.

The hinges used with doors 15 and 16 may be used to define the extreme open position of these doors, or any appropriate stops (not shown) positioned on the cabinet may be used. Suitable hinge arrangements are shown in Patents Nos. 2,230,655 and 1,078,363, for example.

When panel 25 is to be moved between inoperative and operative positions, projections 26 are slid along the guideway formed by guides 19 and 20 and by guide 21 and top panel 14. If desired, pegs 24 may be removed and the rear edge of panel 25 lowered until projections 26 are clear of the guideway between guides 19 and 20. Then by lowering one end of panel 25, the panel may be removed completely from the cabinet. As an interesting but less useful variation of the invention, each door could carry a plurality of spaced projections (not shown) instead of holes 17 and pegs 18, so that the doors could be opened slightly beyond their door supporting positions to permit change in height of the front edge of the desk panel.

I wish it to be clearly understood that the embodiment of the invention as described is only a preferred embodiment and that the invention is susceptible of numerous variations without departing from the inventive concept as defined by the appended claims.

I claim:

1. An article of furniture comprising support-

ing means including spaced walls, a panel having projections at its rear corners extending beyond its end edges, guide means mounted on the inner surface of each of said walls and projecting toward the other of said walls, said guide means including a substantially horizontal guide element mounted near the upper edge portion of each wall and spaced from the upper edge of each wall by a distance at least as great as the thickness of said panel, said guide means also including two substantially vertically disposed elements on each wall, said two elements being spaced from each other to form a guideway communicating with the space above said horizontal guide element and at least as wide as the projections carried by said panel, whereby said projections are slidably receivable in said guideway, an inward projection on at least one of said horizontal guide elements and near the forward end of said elements, for supporting the forward portion of said panel when said panel projections are supported by said horizontal guide elements, means in said vertical guideways forming a plurality of spaced hinge supports for pivotably supporting said panel projections when said projections are located in said vertical guideway, and means forming a plurality of front supports for supporting the forward portion of said panel when said panel projections are located in said vertical guideway, whereby said panel may be located in an inoperative position with the panel projections supported by said horizontal elements and the front portion of the panel supported by the inward projection on said horizontal guide elements, and said panel may also be located with its projections located in said vertical guideway and supported by said hinge means, with the forward portion of the panel supported by said front support means.

2. An article according to claim 1 wherein said hinge means include a plurality of spaced holes located in each of said vertical guideways and a peg receivable by said holes according to the desired height of the hinge.

3. An article according to claim 2, said front support means comprising a pair of doors hinged to the forward edges of said spaced walls, peg and hole means similar to those in the vertical guideway for supporting the forward portion of said panel at variable heights, and means associated with said doors to block their swinging open beyond a position just sufficient to permit said panels to move therebetween.

4. An article of furniture comprising a cabinet having an opening in the front thereof, at least one door hinged at the side of said opening to said cabinet, guideways in the side walls of said cabinet forming a trackway extending horizontally along the upper portion of said walls and vertically down the front portion of said walls, a desk panel having projections in the sides thereof slidably in said trackway, means in said vertically extending trackways, a plurality of hinge supports for pivotably supporting said panel projections when said projections are located in said vertically extending trackways, means in said door forming a plurality of front supports for supporting the front of said panel whereby said desk panel can be supported at a plurality of heights and at a plurality of angles with respect to said cabinet and means associated with said doors to block their swinging open beyond a position just sufficient to permit said panel to move therebetween.

5. An article according to claim 4 wherein said front supporting means comprises peg and hole means.
